UNITED STATES PATENT OFFICE.

SUMNER A. BEMIS, OF SPRINGFIELD, MASSACHUSETTS.

BRAKE-SHOE SUPPORT.

SPECIFICATION forming part of Letters Patent No. 425,974, dated April 22, 1890.

Application filed February 10, 1890. Serial No. 339,928. (No model.)

To all whom it may concern:

Be it known that I, SUMNER A. BEMIS, a citizen of the United States, residing at Springfield, in the county of Hampden and State of Massachusetts, have invented new and useful Improvements in Brake-Shoe Supports and Means for Attaching Same to the Brake-Beams of Cars, of which the following is a specification.

10 This invention relates to car-brakes, the object being to provide improved brake-shoe-supporting devices and improved means for attaching said devices to the brake-beam, whereby the brake-shoe and its holder or support are held in operative relation to each other and are secured to the brake-beam by means of a single bolt, and the brake-shoe, when worn, may be conveniently replaced by another one by simply detaching and reattaching said bolt.

15 In the drawings forming part of this specification, Figure 1 is a side elevation of a section of a car-wheel and of a brake-shoe and brake-holding devices and of devices for locking the brake-holding devices to the brake-beam constructed according to my invention, said figure showing the brake-beam in end elevation in operative relation to the above-mentioned parts. Fig. 2 is a rear elevation 20 of the brake-holder and the beam-locking parts and an edge view of a portion of the brake-beam. Fig. 3 is a plan view. Fig. 4 is a sectional view of the brake-shoe and the brake-shoe holder about on line 4 4, Fig. 1, 25 said figure indicating in dotted lines the position of the tread and rim of a car-wheel in relation to the bearing-face of the brake-shoe.

30 In the drawings, E indicates the brake-beam, made, preferably, of wrought-iron in the form shown, and A indicates a segment of a car-wheel.

35 B is the brake-shoe holder, made, preferably, of cast-iron, having its face suitably curved to receive thereagainst the brake-shoe D. Said 40 brake-shoe holder has a bifurcated bracket 3 formed on its outer side, consisting of the two arms o o, the opening between said arms being sufficiently wide to receive the brake-beam E on the lower one of said arms o, as 45 shown in Fig. 1 and to permit of passing the shank of a bolt 5 between the upper side of

the brake-beam E and the under side of the upper arm o of the bracket 3, the outer edge of said brake-beam projecting slightly beyond the end of said bracket, as shown in Fig. 1. 55 The said brake-shoe holder B has therein, as clearly shown in Fig. 4, a socket or recess e and a bolt-shank passage z, leading from said recess e rearwardly.

The brake-shoe D has a bolt-head chamber c 60 formed therein, one end of which is open on its bearing-face, and at the base of said chamber is an opening x therethrough, through which the shank of the bolt 5 is passed, the rear side of the brake-shoe having a projection thereon 65 opposite said chamber c, which is of suitable form to fit into the said recess e in the face of the brake-shoe holder B.

A clamp-block 4 is constructed to grasp the outer edge of the brake-beam E, and has an 70 opening therethrough to provide for passing the screwed end of the bolt 5 through the upper part thereof, as shown.

In applying the above-described brake-shoe and brake-shoe holder to the brake-beam the 75 said holder has the brake-shoe applied thereagainst, the said projection on the inner side of the brake-shoe entering the recess e in the holder. The bolt 5 is then passed through the opening c in the face of the brake-shoe 80 and through the passage z in the brake-shoe holder, the bolt-head coming to a bearing on the base of said opening c, its screw-threaded end projecting beyond the end of the bracket 3 on the holder. The holder is then placed 85 on the brake-beam in the position shown in Fig. 1, the clamp-block 4 being placed on the end of said bolt and engaging with the outer edge of the brake-beam, as shown, and the nut 8 is then screwed against said clamp-block, 90 thereby firmly locking the brake-beam, brake-shoe, and intermediate brake-shoe holder rigidly together.

To replace a worn-out brake-shoe with a new one is the work of but a few moments 95 and requires only that the bolt 5 be removed, the worn-out shoe be then taken off from the holder B, a new shoe be placed thereon, and the bolt replaced and secured therein by its nut.

100 By means of the within-described devices for securing the brake-shoe and its holder on

the brake-beam the latter is not in the least mutilated, and the holder and the shoe are adjustable longitudinally on the beam to accommodate varying gages of track and 5 wheels.

What I claim as my invention is—

1. A brake-shoe holder having a bifurcated bracket on the outer side thereof to receive the brake-beam, and a recess in its opposite side to receive a projection on a brake-shoe, and a bolt-passage leading from said recess and communicating with the space between the arms of said bracket, substantially as set forth.
2. A brake-shoe holder having a bifurcated bracket thereon to receive the brake-beam, a brake-shoe applied to said holder, a bolt passing through said shoe and holder, and a clamp-block engaged by said bolt and engag-

ing with the brake-beam, combined and operating substantially as set forth. 20

3. A brake-shoe holder having a bifurcated bracket on the outer side thereof to receive the brake-beam, and a recess in its opposite side to receive a projection on a brake-shoe, 25 and a bolt-passage leading from said recess and communicating with the space between the arms of said bracket, combined with a brake-shoe having a projection thereon to enter said recess, a bolt whose head engages 30 with the shoe in said recess, extending from thence through said holder, and a clamp-block engaged by said bolt and engaging with the brake-beam, substantially as set forth.

SUMNER A. BEMIS.
